Primary Examiner — Karen S Acker(74) *Attorney, Agent, or Firm* — Sughrue Mion, PLLC(57) **CLAIM**

The ornamental design for a lenticular lens sheet, as shown and described.

DESCRIPTION

FIG. 1 is a front elevational view of a lenticular lens sheet, showing the claimed design;

FIG. 2 is a perspective view of FIG. 1 as viewed from a perspective diagonally forward left;

FIG. 3 is another perspective view of FIG. 1 as viewed from a perspective diagonally forward right; and,

FIG. 4 is a rear elevational view of the lenticular lens sheet. A lenticular lens sheet has a different appearance based on an angle or perspective of viewing the sheet. The lenticular lens sheet is a flat sheet.
